UNITED STATES PATENT OFFICE

107,370

DESIGN FOR A PIPE SPARK ARRESTER

Charley M. Bly, Cortez, Fla.

Application September 14, 1937, Serial No. 71,614

Term of patent 7 years

To all whom it may concern:

Be it known that Charley M. Bly, a citizen of the United States, residing at Cortez, in the county of Manatee and State of Florida, has invented a new, original, and ornamental Design for a Pipe Spark Arrester, of which the following is a specification, reference being had to the accompanying drawing, forming part thereof, wherein

Figure 1 is a perspective view of the pipe spark arrester showing my new design.

Figure 2 is a vertical section taken on the line 2—2 of Figure 1, and

Figure 3 is a vertical section taken on the line 3—3 of Figure 1.

I claim:

The ornamental design for a pipe spark arrester, as shown.

CHARLEY M. BLY.
